UNITED STATES PATENT OFFICE

WILLIAM FLOYD MCKENNON, OF PORTLAND, OREGON, AND ROY C. BERK, OF SPOKANE, WASHINGTON, ASSIGNEES, BY MESNE ASSIGNMENTS, TO THE STANDARD ELECTRIC TIME CO., OF SPRINGFIELD, MASSACHUSETTS

AUTOMATIC TRAIN ANNUNCIATOR

Application filed December 20, 1928. Serial No. 327,302.

Our invention relates particularly to automatic train announcing devices for railway stations and the like.

Heretofore the mode generally followed in railway stations, stage terminals and the like for announcing the arrival and departure of trains has been to mark the time on a black board and supplement the same by announcements made by means of a megaphone or microphone. Such means, while simple and effective within narrow limits, tend to be unintelligible to the passengers and to add to the confusion of the station.

The object of our invention is to provide an efficient and compact automatic train or stage annunciator adapted for all types of railway or stage stations, marine terminals, air ports and the like, consisting of a surface preferably a curtain mounted on rollers bearing a train schedule and calling attention to such schedule by illuminating a sign bearing a notation to the effect that the train or stage is "Now loading," a predetermined period of time in advance of the departure of the train or stage; further simultaneously with the illumination of said schedule to sound an audible alarm thereby to call attention to the illuminated schedule.

Another object of our invention is to provide the curtain bearing the train or stage schedule with means whereby when a train or stage has departed, the portion of the curtain bearing the schedule will be automatically withdrawn from view, and at the appropriate time another schedule carried by the same curtain substituted in its place, a similar predetermined time before the departure of the next train.

A further object of our invention is to provide in combination with an electrical master clock mechanism, suitable electric relays and circuits for actuating and controlling our train announcing device.

In other words, we provide a train announcing device adapted to automatically and simultaneously display a train schedule a predetermined time before the departure of a train, to illuminate a warning signal, and to actuate an audible signal such as a gong. Then, one minute before the train leaves, to

actuate another audible signal of a distinctive sound as a last call, and then as the train leaves the station to withdraw its schedule and turn out the lights.

A still further object of our invention is 55 to provide manually operated switches for the independent manual control of any or all the functions of our announcing device.

These and other incidental features, the details of construction and the mode of operation of our invention are hereinafter fully described with reference to the accompanying drawings.

In the drawings:

Fig. 1 shows a diagrammatic elevation of 65 our train announcing device, partly broken away to disclose certain details of construction and illustrates diagrammatically the circuits and electrical control means therefor;

Fig. 2 shows an elevation of one panel of 70 the bulletin board, with the front portion removed to illustrate the details of the curtain and operating means;

Fig. 3 shows a section taken on the line 3—3 of Fig. 2; 75

Fig. 4 shows a fragmentary front elevation of two of the program tapes operated by the mechanism of the electric master clock; and

Fig. 5 shows a fragmentary view of the 80 curtain removed from its rollers and illustrates the arrangement of the schedules.

Referring now to the figures, our train announcing device comprises a housing *a*, provided with a number of compartments *b*, 85 separated by a partition *d*, which are similar in construction and only one of which will be described. A frame *c* is provided over each of said compartments which will expose a train schedule, but cover the other 90 mechanism contained therein.

A curtain *e* is arranged in each compartment which is wound at each end on rollers *f*, *g*, journaled in the sides of the compartment and passed over idling rollers *h'*, *i'*. 95 Pulleys *h*, *i* are provided on one end of each of the rollers, respectively. A belt *j* is arranged over the said pulleys and over a driving pulley *k* mounted on the shaft *l* of a reversible motor *m*. 100

In the top of the compartment *b* are provided fingers *s*, *s'*, *s''*, bearing against the curtain *e* and on the underside of the curtain is provided a contact bar *t*, Figs. 1 and 3. Perforations *e'*, *e''*, *e'''*, *e''''*, *e'''''* are provided in the curtain, Figs. 1 and 5, so that as the curtain is wound these perforations will come under the fingers *s*, *s'*, *s''* and permit their contact with the bar *t*. The perforations being arranged to control the starting, stopping and reversing of the curtain, as hereinafter described.

Electric lights *p* are provided in the frame *a* above the compartments *b* and behind a translucent sign *w* bearing the notation "Now loading" or similar information, which are lighted when a train is loading; anaunciating means comprising a gong *q* and chimes *r* of distinctive sounds are provided, arranged in any convenient part of the station relative to our device.

In order that the curtain *e* may be moved to display the required schedule at the proper time and in order that the lights *p* will be illuminated as the curtain is moved and remain so until the train has departed, and in order that the gong *q* will be actuated simultaneously with the displaying of the bulletin and the chimes *r* actuated a minute before the train is due to leave, we have provided suitable electric circuits in combination with well known electric control devices, actuated by an electric master clock, the latter of which we will only described briefly.

Referring to Fig. 1, the only mechanism of the electric clock we have shown is the escapement shaft 2, and a sprocket 3, in mesh with the sprocket on the said escapement shaft which is rotated once a minute, as is usual in such clocks.

Mounted on the shaft 4 of the sprocket 3 are two levers 5 and 6, projecting outwardly in diametrically opposite directions, but on the opposite side of the sprocket 3, respectively. The shaft 4 is connected in a circuit 10 to the negative side of the source of electrical energy or storage battery 11.

The lever 5, as it rotates once a minute is brought into contact with a contact member 7, which is connected in a circuit 12 to solenoids 13 connected with the positive side of the battery 11. These solenoids 13 actuate the program tapes A, B, C, D by means of pawls and ratchets 15, so that the said tapes are actuated once every minute to move them one division on the tape. On the inside face of each tape is provided a contact member 16, which bears lightly against it and is connected in a circuit 17 to a contact member 18 adjacent the lever 6.

The contact member 18 is elongate and resilient, and is arranged adjacent the end of the lever 6 and diametrically opposite to the contact member 7. By this construction the lever 6 will remain in contact with the con-

tact member 18 for several seconds, approximately four, as it rotates, so that the circuit of the contact member 16 is closed for the same period. Fingers 19 are provided bearing against the tape on the other side from the contact member 16, connected in a circuit 20 with the various control relays hereinafter described.

The tapes are provided with perforations, see Fig. 4, spaced at predetermined intervals, according to the time at which a contact between a finger 19 and contact member 16 is to be made, so that as the tapes are moved one division each minute, a perforation will be brought at the predetermined time under the finger 19 and a contact made between it and the contact member 16 for one minute. However, as the lever 6 only remains in contact with the contact member 18 for four seconds, the circuit through the said finger and the said control relays will only be maintained for a like period.

The control relays provided for operating the gong *q* and the chimes *r* comprise simple relays of solenoids 25 and 26^a and switch members 25^a and 26^a, the latter arranged in circuits 27 and 28, respectively, of the said gong *q* and chimes *r*.

By this means as a perforation on the program tape B reaches the finger 18, the circuit through the solenoid 25 is closed and the current through the said solenoid actuates the switch member 25^a to close the circuit of the gong *q* for the period the lever 6 is in contact with the contact member 18.

Similarly as a perforation on the program tape C reaches the finger 19, the chimes *r* will be actuated.

The control relay for operating the lights *p* consists of a locking relay 30 comprising a solenoid 30^a, a pawl and ratchet 30^b, and a notched disc 30^c upon which an arm 30^d rests and which is raised when resting on the top of a notch and lowered when resting in the valley between the notches, in the raised position, closing a circuit 31 to the negative side of the source of power 11 and a circuit 32 to a simple relay 33 in the heavy duty circuit 34 of the lights *p*, and in the lower positions opening the said circuit. So that the first impulse from the tape A will actuate the relays 30 to close the circuit to the relay 33, and a second impulse provided by another perforation in the said tape will be required to open the said circuit to put out the lights *p*.

The controls for operating the curtain are actuated by the tape D, the circuit 20 from the finger 19 being connected to a locking relay 40, similar to the ones previously described except that a double lever 41 is provided consisting of upper and lower parts 42, 43, one part being insulated from the other. The lower part 43 is connected in a circuit 45 with a solenoid 46, of a second

locking relay 47, exactly the same as the locking relays heretofore described, and which is connected to the positive side of the source of energy 11 in a circuit 48.

5 A contact member 42^a adjacent the upper part 42 of the lever 41 is connected in a circuit 56 with a simple relay 60 in the reversing service circuit 48 of the motor *m*. A contact member 20^a of the circuit 20 is arranged adjacent the lower part 43 of the lever 41.

10 The contact 47^a of the locking relays 47 is connected in a circuit 50 in which is a simple relay 51, controlling the circuit 52 of the motor *m*.

15 The solenoid 40^a of the relay 40 is connected in a circuit 61 with the positive side of the source of power and the fingers *s'*, *s²* on the curtain.

20 The finger *s* on the curtain is connected in a circuit 55 with the circuit 20 from the finger 19 of the program tape D.

The contact bar *t* is connected by a circuit 57 with the negative side of the source of power 11.

25 In the operation of our train annunciating device, let us assume the leaving time of a train is nine o'clock and that passengers are allowed to get aboard twenty minutes before the hour.

30 At twenty minutes of nine, the tape A will bring a perforation under the finger 19, which will close the circuit 20 in which is the locking relay 30 which closes the circuit 31 of the lights *p*, causing them to be lighted.

35 Simultaneously, the tape B will bring a perforation at twenty minutes of nine under the finger 19 and close the circuit 20 to the simple relay 25 which controls the gong *q*, by which it will be actuated for four seconds, 40 the time the lever 6 is in contact with the contact member 18.

45 Simultaneously, the tape D will bring a perforation under the finger 19 and close the circuit 20 to the locking relay 47, which passes through the lower part 43 of the lever 42, which is in contact with the contact 20^a of the circuit 20, and actuates the relay 47 to close the circuit 50 and a simple relay 51, in the service circuit 52 of the motor *m* and 50 causes the motor to wind the curtain until a perforation *e'* in the curtain passes under the finger *s*, at the point the schedule is fully displayed and closes the circuit 55 which actuates the relay 47 again to open the circuit 50, stopping the motor, thus leaving the curtain displaying the proper schedule.

55 Then one minute before the leaving time of the train, the program tape C will bring a perforation under the finger 19 and close the circuit 20 to the simple relay 26, which controls the circuit 28 of the chimes *r* and holds the said relay closed for four seconds, during which the warning bell will be actuated.

60 Finally, as the leaving time of the train

is reached, another perforation on the tape A will pass under the finger 19 and close the circuit 20 to the locking relay 30, which will be actuated to open the circuit 31, and discontinue the lights *p*.

70 The tape D will simultaneously bring another perforation under the finger 19 which will actuate the relay 47 as before described which will cause the motor *m* to wind the curtain until the schedule has disappeared from view, when another perforation *e²* on the curtain will pass under the finger *s* and cause the motor *m* to stop.

75 When the end of the curtain is reached, a perforation *e³* will be brought under the finger *s* which will stop the curtain and at the same time a perforation *e⁴* will be brought under the finger *s* and will close the circuit 56 and actuate the locking relay 40 to bring the upper part 42 of the lever 41 to bear on the contact member 45^a and actuates the relay 46 to close the reversing circuit 48 of the motor *m*.

80 The curtain will then rewind until a perforation *e⁵* at the beginning of all the schedules on the curtain will pass under the finger *s²*, and close the circuit 56 and actuate the relay 40 to open the reversing circuit of the motor and stop it, simultaneously moving the lower part 43 of the lever 41, into contact again with the contact member 20^a of the circuit 20, so that it is in position for the next impulse from the tape D to start the motor *m* again to display another schedule as the time arrives.

85 90 95 100 Of course, if the leaving time of a number of trains overlaps twenty minutes the lights *p* may remain lighted and the gong *q* and chimes *r*, will be actuated independently for each train and as one train leaves before another their respective schedules will be withdrawn, so that no confusion will result from the said overlapping of their leaving time.

105 Furthermore, we have provided emergency manually operated switches 70, 71, 72, 73 and 75 in the various circuits, so that any one of the functions of our train annunciating device may be actuated independently should the occasion arise, such as for special or delayed trains, or stages.

115 We claim:

1. An automatic train annunciator, and the like, comprising a surface bearing an announcement, a clock mechanism, means actuated by said clock mechanism for illuminating said announcement for a predetermined period of time, and means actuated by said clock mechanism adapted to give an audible alarm simultaneously with said illumination.

120 125 130 135 2. An automatic train annunciator, and the like, comprising a surface bearing an announcement, electric means actuated by said clock mechanism for illuminating said announcement for a predetermined period of

time, and electric means actuated by said clock mechanism adapted to give an audible alarm simultaneously with said illumination.

3. An automatic train annunciator, and the like, comprising an illuminable announcement, a rolled curtain bearing data complementary to said announcement, a clock mechanism, means actuated by said clock mechanism for unrolling said curtain, means actuated by said clock mechanism for illuminating said announcement for a predetermined period of time, and means actuated by said clock mechanism adapted to give an audible alarm simultaneously with said illumination.

4. An automatic train annunciator, and the like, comprising an illuminable announcement, a rolled curtain bearing data complementary to said announcement, a clock mechanism, electric means actuated by said clock mechanism for unrolling said curtain, electric means actuated by said clock mechanism for illuminating said announcement for a predetermined period of time, and electric means actuated by said clock mechanism adapted to give an audible alarm simultaneously with said illumination.

5. An automatic train annunciator, and the like, comprising an illuminable announcement, a rolled curtain bearing data complementary to said announcement, a clock mechanism, means actuated by said clock mechanism for unrolling said curtain, means actuated by said clock mechanism for illuminating said announcement for a predetermined period of time, means actuated by said clock mechanism adapted to give an audible alarm simultaneously with said illumination, and means actuated by said clock mechanism for giving a second audible alarm distinguishable from the first-mentioned alarm, and thrown into action a predetermined period preceding the termination of said period of time.

6. An automatic train annunciator, and the like, comprising an illuminable announcement, a rolled curtain, bearing data complementary to said announcement, a clock mechanism, electric means actuated by said clock mechanism for unrolling said curtain, electric means actuated by said clock mechanism for illuminating said announcement for a predetermined period of time, electric means actuated by said clock mechanism adapted to give an audible alarm simultaneously with said illumination, and electric means actuated by said clock mechanism for giving a second audible alarm distinguishable from the first-mentioned alarm and thrown into action a predetermined period preceding the termination of said period of time.

7. An automatic train annunciator, and the like, comprising an illuminable announcement, a rolled curtain bearing data complementary to said announcement, a clock mechanism, means actuated by said clock mechanism for unrolling said curtain, means ac-

tuated by said clock mechanism for illuminating said announcement for a predetermined period of time, means actuated by said clock mechanism adapted to give an audible alarm simultaneously with said illumination, means actuated by said clock mechanism for giving a second audible alarm, thrown into action a predetermined period preceding the termination of said period of time, and means actuated by said clock mechanism for re-rolling said curtain.

8. An automatic train annunciator, and the like, comprising an illuminable announcement, a rolled curtain bearing data complementary to said announcement, a clock mechanism, means actuated by said clock mechanism for unrolling said curtain, means actuated by said clock mechanism for illuminating said announcement for a predetermined period of time, means actuated by said clock mechanism adapted to give an audible alarm simultaneously with said illumination, means actuated by said clock mechanism for giving a second audible alarm, thrown into action a predetermined period preceding the termination of said period of time, means actuated by said clock mechanism for re-rolling said curtain, and manual means adapted for actuating either of said other means independently of said clock mechanism.

9. An automatic train annunciator, and the like, comprising an illuminable announcement, a rolled curtain bearing data complementary to said announcement, a clock mechanism, electric means actuated by said clock mechanism for unrolling said curtain, electric means actuated by said clock mechanism for illuminating said announcement for a predetermined period of time, electric means actuated by said clock mechanism adapted to give an audible alarm simultaneously with said illumination, electric means actuated by said clock mechanism for giving a second audible alarm distinguishable from the first-mentioned alarm and thrown into action a predetermined period preceding the termination of said period of time, electric means actuated by said clock mechanism for re-rolling said curtain, and manual means adapted for actuating either of said other means independently of said clock mechanism.
